UNITED STATES PATENT OFFICE.

EVERETT G. LIVESAY, OF PRINCETON, WEST VIRGINIA, ASSIGNOR, BY MESNE
ASSIGNMENTS, TO SAFETY MAIL CRANE COMPANY, OF CHARLESTON, WEST
VIRGINIA, A CORPORATION OF WEST VIRGINIA.

MAIL-BAG CRANE.

1,344,912.

Specification of Letters Patent. Patented June 29, 1920.

Application filed April 7, 1919. Serial No. 287,959.

To all whom it may concern:

Be it known that I, EVERETT G. LIVESAY, a citizen of the United States, residing at Princeton, in the county of Mercer and 5 State of West Virginia, have invented certain new and useful Improvements in Mail-Bag Cranes, of which the following is a specification.

My invention relates to improvements in 10 mail bag cranes.

An important object of the invention is to provide a mail bag crane, having arms which are adapted to be set substantially parallel to the track and are swung to a 15 position at substantially a right-angle to the track, upon the approach of a train, such crane having means to accelerate its starting movement, so the arms are swung to the inner position, in proper time to meet 20 the catcher carried by the train, the movement of the crane decreasing as the arms approach the inner position, whereby the apparatus is relieved of undue shocks upon the stopping of the same.

25 A further object of the invention is to provide means whereby the crane may be moved or turned by a plurality of weights, passing over pulleys, and which are supported to automatically shift with the crank 30 of the crane.

35 A further object of the invention is to provide adjustable means whereby at least one of the arms of the crane may be shifted longitudinally of the post of the crane and locked to the same in the adjustable position for connection with mail bags of different 40 lengths.

45 A further object of the invention is to improve the construction of the trip apparatus, simplifying the same, and rendering it stronger.

Other objects and advantages of the invention will be apparent during the course of the following description.

45 In the accompanying drawings forming a part of this specification and in which like numerals are employed to designate like parts throughout the same:

50 Figure 1 is a side elevation of the mail crane embodying my invention, showing the same associated with the track trips;

Fig. 2 is a plan view of the same;

Fig. 3 is an enlarged side elevation of the crane, parts being broken away, and

parts being in section for the purpose of 55 illustration;

Fig. 4 is a horizontal sectional view, taken on line 4—4 of Fig. 3;

Fig. 5 is a similar view, taken on line 5—5 of Fig. 3; 60

Fig. 6 is a vertical sectional view, taken on line 6—6 of Fig. 3;

Fig. 7 is a fragmentary side elevation of the track trip;

Fig. 8 is a transverse sectional view, taken 65 on line 8—8 of Fig. 7;

Fig. 9 is a similar view, taken on line 9—9 of Fig. 7;

Fig. 10 is a detail horizontal section, taken 70 through one end of the arms of the crane;

Fig. 11 is a detail section through the longitudinally adjustable sleeve carrying the adjustable arm of the crane;

Fig. 12 is a horizontal sectional view, taken on line 12—12 of Fig. 11; and 75

Fig. 13 is a side elevation of a railway mail coach showing the apparatus carried thereby for operating the track trip or ramp.

In the drawings, wherein for the purpose 80 of illustration is shown a preferred embodiment of my invention, the numeral 15 designates railways of a track, secured to the cross ties 16, in the usual manner.

The numeral 17 designates a crane disposed upon one side of the track, and at a suitable distance therefrom. This crane embodies a casing or housing 18, which is rigidly secured to certain of the cross ties 15, which may be extended for that purpose. 90 The casing 18 is provided with a closed top 19 provided with an upstanding flange or bearing 20, rotatably receiving a sleeve 21, carrying a cap 22, which overhangs the bearing 20 and protects the same to prevent 95 rain, snow, or the like entering the space between the bearing 20 and the sleeve 21.

The numeral 23 designates a vertical preferably tubular support or post, extending through the sleeve 20, and rigidly secured 100 thereto by solder 24 or the like, so that these elements rotate together. The upper end of the post 23 projects beyond the casing 18 for a substantial distance, and its lower end receives a coupling plug 24 rigidly secured thereto by a transverse pin or rivet 25. This coupling plug carries a head 26, preferably formed integral therewith. The

head 26 is rotatable within a flange or bearing 27, preferably formed integral with the floor or bottom 28 of the casing 18, there preferably being a space 29 surrounding the head 26.

Connected with the upper end of the tubular post 23 is a horizontal coupling 30, which is U-shaped in cross section, and has its top open. The numeral 31 designates 10 the upper vertically swinging arm of the crane, and this arm is pivoted within the coupling 30, as shown at 32, to swing in a vertical plane with relation thereto. The coupling 30 prevents the arm from being 15 swung down beyond a substantial horizontal position, while this arm is swung to a vertical position, when released, by a weight 32, secured to the free end thereof. Arranged beneath the upper arm 31 is a 20 coacting vertically swinging arm 33, provided at its inner end with a lateral extension or crank 34, adapted to clamp against the post 23. The inner end of the arm 33 is pivoted, as shown at 35, with a 25 vertically adjustable sleeve 36, slidably receiving the post 23. As more clearly shown in Fig. 12 this sleeve 36 is provided with a longitudinal groove 37, receiving a longitudinal key 38, rigidly secured to the post 23, whereby this sleeve is free to move 30 longitudinally of the post 23 but cannot turn with relation thereto.

As more clearly shown in Fig. 10, each of the arms 31 and 33 is tubular and has fingers 39, pivoted therein, as shown at 40, such fingers being adapted to partake of restricted horizontal swinging movement within an opening 41, the inner end of these fingers being tapered, as shown at 42. 40 Spring clips 43 are secured to the top and bottom of these fingers 39, and engage with the rings or loops 44, carried by the opposite ends of the mail bag 45. From the foregoing description, it will be seen that 45 the lower arm 33 may be vertically adjusted to the desired position, by moving the sleeve 36 longitudinally of the post 23, whereby the arms 31 and 32 may be arranged at suitable distances, for receiving and holding 50 taut the mail bag 45 of any ordinary length. The mail bag exerts an upward pull upon the arm 33 which tends to swing upon its pivot 35, whereby the crank or cam 34 clamps against the post 23, thereby locking 55 the sleeve 36 against upward movement. As soon as the mail bag is pulled from the arms 31 and 33, these arms assume vertical positions, thereby providing ample clearance upon the side of the train.

60 Means are provided to turn the crane, upon the approach of the train to the same, whereby the arms are swung from a position parallel to the track, to a position at a right angle thereto. Such means comprises 65 a horizontally swinging crank 46, rigidly

secured to the post 23, within the casing 18, as shown at 47. This crank is provided at its free end with an eye 48, for connection with a pair of cables 49, which pass about grooved pulleys 50. These grooved pulleys 70 are pivoted in horizontally swinging carriers 51, in turn pivoted to stationary brackets 52, by tubular pins 53, such pins extending through depending extensions 54 of the brackets. The brackets 52 are rigidly secured or bolted to the casing 18, as shown at 55. The cables 49 extend through the tubular pins 53 and are connected with bolts 56, which are adjustably mounted within openings 57 formed in the upper end 75 of weights 58. These weights have main bores 59, to receive compressible coiled springs 60 surrounding the bolts 56. The bolts are screw threaded at their lower ends, receiving nuts 61, which engage the washers 62, and are adapted to regulate the tension of the springs 60, when the weights 58 are drawn upwardly sufficiently to contact with the extensions 54. It might be stated at this point, that when the arms of the crane are swung in either direction to assume a position parallel to the track, as shown in Fig. 2, one weight 58 is elevated so that it contacts with the extension 54 and places the spring 60 under compression. It will be seen that when the locking means, to be described, which holds the post 23 against turning movement, releases the post, the post is turned rapidly upon its longitudinal axis at the starting of its movement, for 100 such turning movement is then effected by the combined force of the weight 58 and the expanding action of the spring. However, when the weight moves downwardly, a slight distance or approaches the lower end 105 of its travel, the function of the spring 60, as above indicated, ceases and the turning movement of the crane is slower, being due solely to the action of the weight. When the weight reaches the end of its down travel, the spring 60 then functions to absorb the shocks in the stopping of the weight.

The means to lock the post 23 against turning movement when the arms are set in either position parallel to the track, consists of a reciprocating bolt 61' mounted to reciprocate within a housing 62', as shown in Figs. 5 and 6. This bolt has a tapered end 63, adapted to enter openings or notches 64, formed in the head 26, at preferably diametrically opposite points. The bolt 61' is connected with a preferably tubular rod 65, by a coupling 67. This rod 65 extends through an opening in the wall 68 of a 115 housing 69, which is bolted to the cross ties 16, inwardly of the casing or housing 18, as shown. The compressible coil spring 70 surrounds the screw threaded portion 71 of the rod 66, and contacts with the nut 72, en- 120 130

gaging the screw threaded portion, this nut being adapted to be locked in an adjusted position by a lock nut 73. The opposite end of the screw threaded portion 71 has screw 5 threaded engagement with a head 74, provided with elongated slots 75 receiving bolts 76, carried by bell crank levers 77, pivoted at 78. These bell crank levers have pivotal connection with rods 79, extending in opposite directions of the crane and parallel with the track, for connection with trips or ramps 80, to be next described.

These trips are arranged upon opposite sides of the crane at suitable distances therefrom such as 90-feet. Each trip comprises a pair of inclined rails 81, preferably T-rails shown in cross section, as shown in Fig. 9. These rails 81 extend downwardly toward their outer ends, and these outer ends are 10 pivoted, as shown at 82, with fixed brackets 83, secured to the cross ties. One rail 81 is rigidly connected with a triangular plate 84, by means of bolts 85. This plate has connection with a bolt 86, operating through an elongated slot 87, in the inner end of the other rail 81. The lower end of the triangular plate 84 has pivotal connection with a horizontal crank 88, rigidly secured to a rock shaft 89 journaled in a stationary 15 sleeve or bearing 90. A vertical crank 91 is rigidly secured to the shaft 89. The rod 79 is secured to the vertical crank 91. It is thus seen that when the rails 81 are depressed, the cranks 88 and 91 will turn upon 20 their pivots, and the rod 79 be drawn longitudinally, which movement is imparted to the bolt 61', to withdraw it from the opening or notch 64, whereby the post 23 is free to turn.

40 In Fig. 13, the numeral 92 designates the fork of the mail bag catching device, carried by the mail car 93. This device is adapted to be swung transversely of the car to assume a horizontal position, and this 45 turning movement is effected by a handle 94, the device being carried by a rock shaft 95. When the fork 92 is swung to the outer horizontal position, a cable 96 is pulled downwardly, opening a valve 97, whereby 50 compressed air is supplied through a pipe 98, leading into a cylinder 99. A piston 100 is mounted to reciprocate within this cylinder, and is thereby forced downwardly in opposition to a spring 101, which moves the 55 piston upwardly. When the piston descends, the rod 102 is moved downwardly carrying at its lower end a roller 103, which contacts with the rails 81, and serves to depress them. When the arm 92 is returned to 60 the lowered position, the pressure is exhausted from the cylinder 99 and the roller 103 is elevated. The apparatus carried by the mail car 93 is shown and described in my former patent numbered 1,262,069, 65 granted under date of April 9, 1918, and is

not claimed *per se* in this application, it being understood that this structure is shown simply for the purpose of illustration and any other suitable means may be carried by the train or mail car to depress the rails 81. 70

The operation of the apparatus is as follows:

If the train is traveling from right to left, Fig. 2, the arms 31 and 33 of the crane are set parallel to the track and extend to 75 the right, in an opposite direction to the travel of the train. When the train approaches the trip 80 to the right, and if it is desired to transfer the mail bag from

the crane to the mail bag car, the fork 92 is 80 swung to the horizontal mail bag catching position and the roller 103 is thereby lowered, whereby it contacts with the rails 81 and depresses the same. This depression of the rails 81 releases the post 23, which is 85 turned counter-clockwise, whereby the arms 31 and 33 move in the same direction with the train. The trips are so located with respect to the crane that these arms will be approaching the end of their travel 90

in the direction of the train, but are still moving, when the fork 92 removes the mail bag 45 from the arms of the crane, thereby eliminating unnecessary shocks and jars. 95 When the post 23 is first released, the spring 60 in the weight 58 to the left, is under compression, and this spring coacts with the weight in quickly turning the shaft, whereby the arms 31 and 32 will be shifted to the 100 approximately correct position, by the time the mail car reaches the same. If the spring were not provided, the size of the weight or weights would have to be materially increased, and this would result in excessive 105 strains and jars to the apparatus when the movement of the post 23 is stopped. How-

ever, the springs 60 only function in the capacity of turning the post 23 at the starting of the turning movement, and at the stopping of the turning movement they 110 serve to take up the shocks and jars. As soon as the mail bag is removed from the arms 31 and 33 they automatically shift to vertical positions thereby providing ample 115 clearance upon the side of the track.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In a mail bag crane of the character described, an upstanding post adapted to be turned upon its longitudinal axis, a crank connected with the post to turn it, a substantially horizontally swinging carrier ar- 130

ranged upon one side of the crank, a pulley connected with the carrier, a flexible element connected with the crank and passed about the pulley, a spring secured at its lower end to said flexible element, and a weight having a bore receiving said spring and having a portion adapted to engage the upper end of said spring.

2. In a mail bag crane of the character described, a casing, an upstanding post operating within the casing and projecting above the same, mail bag handling means connected with the upper portion of the post, a horizontally swinging crank connected with the post and arranged within the casing, horizontally swinging carriers arranged within and secured to the casing and positioned upon opposite sides of the crank, flexible elements connected with the crank and passed about the pulleys, springs secured to the flexible elements, weights carried by said springs and means to normally hold the post against turning movement.

3. In a mail bag crane of the character described, an upstanding post adapted to be turned upon its longitudinal axis, mail bag handling means connected with the post, a spring and weight connected with the post to turn it, and means whereby the combined forces of the spring and weight are employed for turning the post at the starting of such movement and the turning action of the spring is cut out after the post has been moved for a predetermined extent.

4. In a mail bag crane of the character described, an upstanding post adapted to be turned upon its longitudinal axis, mail bag handling means connected with the post, a weight connected with the post to turn it, and a spring arranged to be compressed by the weight when in the elevated position to aid the weight in turning the post at the starting of the turning movement, the compression of the spring being dispensed with when the weight descends for a predetermined distance.

5. In a mail bag crane of the character described, an upstanding post adapted to be turned upon its longitudinal axis, mail bag handling means connected with the post, a flexible element connected with the post to turn it, a compressible coil spring connected with the flexible element, a weight carried by the flexible element and arranged above the spring to engage it, and a stop arranged above the weight to contact therewith and cause the weight to compress the

spring when in the elevated position, the spring being released when the weight disengages the stop.

6. In a mail bag crane of the character described, an upstanding post adapted to be turned upon its longitudinal axis, mail bag handling means connected with the post, a flexible element connected with the post to turn it, a compressible coil spring carried by the flexible element, a weight having a recess to receive the spring with its upper portion engaging the spring, and a stop arranged above the weight to contact therewith when the weight is elevated to compress the spring.

7. In a mail bag crane of the character described, an upstanding post adapted to be turned upon its longitudinal axis, mail bag handling means connected with the post, a crank connected with the post to turn it, brackets arranged upon the opposite sides of the crank, pulleys connected with the brackets, cables connected with the crank and passed about the pulleys, compressible coil springs carried by the cable, weights supported by the springs and adapted to be shifted upwardly to a position to contact with the brackets and compress the springs, and means to hold the post against turning movement.

8. In a mail bag crane of the character described, an upstanding post adapted to turn upon its longitudinal axis, a crank connected with the post to turn it, pulleys arranged upon the opposite sides of the crank, cables connected with the crank and passed about the pulleys, compressible coil springs carried by the pulleys, and weights supported by the compressible coil springs.

9. In apparatus of the character described, means for handling a mail bag and adapted to be shifted toward and away from the track, and a device to shift the means toward the track including a flexible element, a compressible spring carried thereby, a weight arranged above the spring and supported thereby, and an element arranged above and in the path of travel of the weight to engage the weight when it is elevated for compressing the springs.

In testimony whereof I affix my signature in presence of two witnesses.

EVERETT G. LIVESAY.
